UNITED STATES PATENT OFFICE.

JEAN JOSEPHS AND DAVID THEODORE BERLIZHEIMER, OF PHILADELPHIA, PENNSYLVANIA, ASSIGNORS OF ONE-THIRD TO GUSTAVUS JOSEPHS, OF PHILADELPHIA, PENNSYLVANIA.

AUTOMATIC WINDING MACHINE.

Application filed August 21, 1924. Serial No. 733,412.

To all whom it may concern:

Be it known that we, JEAN JOSEPHS, a citizen of the United States, residing at Philadelphia, county of Philadelphia, State of Pennsylvania, and DAVID THEODORE BERLIZHEIMER, a citizen of the United States, residing at Philadelphia, county of Philadelphia, State of Pennsylvania, have jointly invented a new and useful Automatic Winding Machine, of which the following is a specification.

In our prior Patents No. 1,298,221, dated March 25, 1919, and No. 1,437,976, dated Dec. 5, 1922, we have disclosed an automatic winding machine wherein a plurality of quills, cops, bobbins or spools are wound with thread drawn directly from the skeins without rendering it necessary to first wind the thread upon spools; and wherein if in the course of winding any particular quill or the like the feed of the yarn should be interfered with, certain mechanism which effect the winding operation will automatically be stopped.

The automatic winding machine as embodied in the present invention involves some of the generic principles of our prior patents aforesaid augmented in efficiency and commercial usefulness by reason of certain novel constructions, a synopsis of which follows:

The leading object of the present invention is to provide an arrangement, connection and combination of parts for an automatic winding machine of the character disclosed in our said patents whereby a more efficient, accurate, positive and generally improved functioning of parts ensues to increase the commercial betterment thereof. A further object of the present invention resides in the provision of details of construction arranged to attain the results sought by said leading object among which may be mentioned the following:

(a) A novel arrangement of drive mechanism including a pair of eccentrically operating gear wheels for causing the main drive shaft to function at variable speeds, whereby a quill or the like is caused to revolve slowly as thread is fed along the major portion of its length and is caused to revolve more rapidly as the thread is fed to the tapering end portion thereof. Such variable speeds as imparted to the quill or the like result in the

swift acquiring uniform speed in its revolution.

55

(b) A novel arrangement of drive mechanism including step-up gear wheels supplementing the ratchet feed illustrated in our Patent Number 1,437,976 for attaining predetermined differences in speed for a thread carrier to compensate for various thickness of thread being wound.

65

(c) A novel arrangement of drive mechanism including a box-cam for imparting a variable speed to the machine carriage in its reciprocating movement.

75

(d) A novel arrangement of coupling for the main driving shaft and for the carrier-box lead-screw whereby through the instrumentality of universal connections perfect alignment of coupled parts is attained.

80

(e) A novel arrangement of carrier-box including automatic, quick-acting, stop mechanism operable (1) in conjunction with machine kick-off whereby a quill or the like is prevented from rotating and the carrier-box is locked against longitudinal movement, and (2) in conjunction with an automatic swift stop, whereby in the event of thread tangling, the carrier feed, quill and thread feed automatically cease to function until manually re-set by the operator.

75

(f) A novel arrangement of tensioning for thread as fed to a quill or the like including a fixed incline positioned parallel with the longitudinal axis of a quill whereby as the thread is fed to the quill, the thread guide moves along said incline to equalize the tension of the thread upon the quill.

85

(g) A novel arrangement of spindle parts including a floating drive upon a quill spindle whereby a pulley becomes self-seating when advanced to a spindle operating wheel.

90

(h) A novel arrangement of quill automatic stop for preventing quill rotation upon completion of a winding operation, the stop mechanism being capable of being adjusted to stop a quill independently of another quill or stop all quills or spindles at the same time.

95

The invention consists of the novel construction hereinafter described and finally claimed.

The nature, characteristic features and scope of the invention will be more fully understood from the following description

100

105

taken in connection with the accompanying drawings forming part hereof, and in which:

Fig. 1, is a top or plan view of so much of an automatic winding machine as is necessary to an understanding of the invention.

Fig. 2, is a view taken upon the line 2—2 of Fig. 1, viewed in the direction of the arrows.

Fig. 3, is a view in front elevation of Fig. 1.

Fig. 4, is a fragmentary view, partly sectioned, of certain of the mechanism parts shown at the upper left hand side of Fig. 3.

Fig. 5, is a view in section taken upon the line 5—5 of Fig. 4.

Fig. 6, is a fragmentary view partly in section and partly in elevation of certain of the parts shown in Fig. 4.

Fig. 19, is a view in section taken upon the line 19—19 of Fig. 10, and

Fig. 20, is a view in section taken upon the line 20—20 of Fig. 10.

For the purpose of illustrating our invention we have shown in the accompanying drawings one form thereof which is at present preferred by us, since the same has been found in practice to give satisfactory and reliable results, although it is to be understood that the various instrumentalities of which our invention consists can be variously arranged and organized and that our invention is not limited to the precise

arrangement and organization of the instrumentalities as herein shown and described.

Referring now to the drawings in detail, the numeral 1 designates a vertical stand-

70

ard, of which two are employed, one at each end of the machine. The numeral 2 designates a horizontal bed plate supported upon the standards 1. The machine may be of

75

any desired length so that any required number of quills, cops, bobbins or spools

80

may be operatively arranged thereon. The machine is constructed for duplicate sets of

85

quills, cops, bobbins or spools, one set upon each side of the machine throughout its ex-

tent. Arranged at one end of the machine

is a head 3 supported upon a stand 4 in which head is arranged drive mechanism a

85

description of which will now be given. Mounted in the head 3 is a shaft 5 rotatable

upon which is a clutch drum 6, motion be-

ing imparted thereto through a belt 7 pass-

90

ing around a pulley fixed to shaft 8. This

shaft 8 is driven by means of an electric mo-

tor 9 connected to said shaft 8 by means of

95

a belt 10. These parts are best seen in Figs.

2 and 3 and a duplicate arrangement of

parts is to be found upon each side of the

95

machine although a description of one will

suffice. Cooperatively arranged with respect

to clutch band 11 is a clutch 6 which rotates

100

a gear wheel 12 which, in the operative position of the clutch 6, is in mesh with a gear

105

wheel 13 fixed to cross shaft 14. Fixed to

110

cross shaft 14 is one of a pair of novel gear

115

wheels eccentrically arranged for imparting

120

a variable speed to the drive shaft which re-

volves the quills, cops, bobbins, or spools.

The numeral 15 designates the eccentric gear

125

wheel upon cross shaft 14, which gear wheel

130

is in mesh with the other eccentric gear

135

wheel 16 which is mounted upon the clutch

140

6. Eccentric gear wheel 16 has formed in-

145

tegral therewith, a bevel gear wheel 17,

150

155

18, mounted upon a longitudinal stud shaft

160

19 coupled, in a manner to be presently de-

165

scribed, with the longitudinal main drive

170

shaft 20 which revolves the quills, cops,

175

bobbins or spools. Also located upon cross

180

shaft 14 is a gear wheel 21 meshing with a

185

gear wheel 22 upon a cross shaft 23 located

190

in a plane below that of shaft 14. Fixed

195

upon shaft 23 is a box cam 24, best seen in

200

Fig. 3, for positively driving the machine

205

carriage through the instrumentality of a

210

vertically disposed lever 25 and its adjuncts

215

which lever is pivoted as at 26 to a bracket

220

27 bolted between the frame 1 and stand 4.

225

The lever 25 is operated by means of a con-

230

nection comprised of a bell-crank lever, ful-

235

crumed as at 29, one arm 28 of which en-

240

gages within the cam groove of the box

245

cam 24 and the opposite arm of which is ad-

250

justably connected to the lever 25 by means

of a link 30 the length of which may be increased or diminished to regulate carriage movement. In the instance shown the bell crank 31 is slotted upon an arc of a circle 5 to accommodate a shoe 32, adjustable therein, pivotally connected to link 30, and adapted to be clamped in adjusted position by means of screws 33, the link being in two sections and adjustable longitudinally. In 10 order to obtain various, predetermined strokes of the machine carriage relative to the quills, cops, bobbins or spool, use is made of step-up gears located in the head 3 and which step-up gears are supplemental to a 15 ratchet movement also located in the head and fully shown and described in our said Patent #1,437,976. Briefly stated, the ratchet in question which is designated 34 in Figs. 4 and 6, is mounted upon a cross shaft 20 35 and is operable through the instrumentality of a pawl 36 actuated by an eccentric 37 upon shaft 14 through the medium of a vertically reciprocating connecting rod 38. Shaft 35 in turn carries a bevel gear wheel 39 in mesh with a bevel gear wheel 40 upon a short shaft 41 supported in head 3, see Fig. 5. Mounted upon shaft 41 is a gear wheel 42 adapted to be selectively caused to mesh with speed change or step-up gear 25 43, 44, 45, or 46 through the instrumentality of a hand lever 47. The head 3, as shown in Fig. 3, is slotted at 48 to accommodate lever 47 and is provided with notched side walls as at 49 to cooperatively 30 receive the lever 47 when moved to the various positions necessary to attain meshing relation of the gears aforesaid. The stud 35 shaft 50 upon which the gear wheels 43, 44, 45, and 46 are mounted is adapted to be 35 coupled as hereinafter described with the lead screw 51 which imparts longitudinal movement to the thread carriers, either to accelerate or retard such movement in accordance with the thickness of thread employed.

Having described the various drive mechanisms as contained within head 3, a description will now be given of a novel form of coupling employed in aligning the stud shaft 19 with the quill, cop, bobbin or spool revolving shaft 20 and in aligning the stud shaft 50 with the lead-screw 51 which operates the thread carriers. Since the couplings, four in number, are duplicates of one another a description of one will suffice. The coupling is of the universal type, in that any inequalities in shaft alignment is corrected. Each coupling consists of a pair of sockets 52 each fitting over a shaft end. Each socket is provided with feet 53 which project from a socket. Between the feet of opposed sockets is arranged a relatively pliable or yielding disc 54 of rubber or the like, the feet of the respective sockets being bolted together to securely clamp the

shaft ends together. Thus, since the disc 54 is relatively yielding, any error in shaft alignment is compensated for which is of vital importance in a machine of the character under consideration because of 70 the nicety of adjustment and precision of part movements required in operating upon silk or other thread.

Having traced and described the various operating means in the head 3, and the 75 coupling and connection of said parts with the carriage, quill, spindle and lead-screw, these latter parts will now be referred to. In the connection, it may be stated that these elements, for the most part, are fully 80 shown and described in our aforesaid Patent #1,437,976, and need therefore be but generally referred to. Secured to bed plate 2 of the machine is a bracket 55, of which there may be any number, for pivotally supporting as at 56, see Fig. 17, a quill spindle casing 57, rotatably mounted in which is a quill spindle 58 which detachably carries a quill 59 upon which thread is to be wound. The quill spindle 58 is driven from main driving shaft 20 by means of a drive wheel 60, having a convexed peripheral rim for frictionally engaging a pulley 61 located upon spindle 58. The pulley 61 has a concaved or recessed periphery so that the drive wheel 60 may cooperate therewith in operative position of the quill. In the connection it is to be noted that the pulley 61, as the spindle moves to operative position around its pivot point, should seat upon the periphery of wheel 60 without binding. To compensate for this we have devised a novel end-slip movement for the floating pulley 61, see Fig. 18. The spindle 58 is made in two parts, the end 62 having a screw-threaded stem 63 which is received in a screw threaded aperture in the end of the spindle 58. The end 62 has a collar 64 and has also keyed relation with pulley 61. Thus the pulley has limited endwise floating movement between collar 64 and shoulder 65 of spindle 58 so that when spindle and quill move to operative position as shown in Fig. 17, the pulley 61 will self-seat itself with respect to drive wheel 60. 115 Also carried by and fixed to bracket 55 is an inclined track arranged in parallelism with the horizontal axis of spindle 58 and quill 59, see Fig. 17. This is so that thread may be properly guided from a thread carrier to the quill for even and uniform winding thereon, as will hereinafter be more particularly referred to. The carriage upon which the thread carriers are mounted, and which is operated by the lever 25, hereinbefore referred to, see Fig. 3, is designated 65 and is best seen in Fig. 3. The carriage 65 is mounted upon rollers 66 which track upon spaced rails 67 and is pivotally connected to lever 25, by means of rod 68, for recipro-

cation longitudinally before the quills, cops, bobbins or spools in the same manner as described in our aforesaid Patent #1,437,976.

A description of the thread carriers, of which there is one for every quill, cop, bobbin or spool, and which carriers have longitudinal movement independently of the carriage movement, will now be given. Primarily, a thread carrier is operable by means of lead screw 51 which derives its motion from the gears in the head of the machine as previously described. The thread carrier and its adjuncts are contained in a carrier box as it is sometimes called, which is designated 68, and is best seen in Figs. 11, 12, and 13. The parts as contained in said carrier box comprise an automatic, quick acting, stop mechanism as follows: (a) mechanism which works in conjunction with the machine "kick-off" whereby a quill, cop, bobbin or spool is stopped from rotation; and longitudinal movement of the carrier box is stopped. (b) Mechanism which also stops automatically the swift stop to prevent tangling or breaking of thread.

Referring now to these parts in detail, thread 69 is guided from a swift 70 in a vertical manner behind fingers 71 fixed to a pivoted and normally vertical arm 72. The thread keeps the arm 72 in the position shown in Fig. 11, but should the thread for any reason break, or the end of the thread appear, the arm 72 through the force of gravity moves inwardly about its pivot thus causing tappet arm 74 which is also fixed upon the same pivot rod 73 as arm 72 to trip arm 75 of detent 77, pivoted as at 76, to release horizontally movable, spring controlled plate 78. This plate 78 in turn moves to the right, in Figs. 11, and 12, the lever 79 which is pivoted as at 80, and which is provided with a lug 81. This lug normally retains elevated a triangular shaped member 82, pivoted at 83, and bearing upon a lever 85, pivoted at 86. As lug 81 withdraws from support of member 82 the latter moves around its pivot point 83 and thereby permits arm 85 to be moved around its pivot 86 by spring 87. The result is that the split feed nuts 89, see Fig. 14, are disengaged from lead screw 51 whereby stoppage of a thread carrier-box is accomplished. The split feed nuts 89 are connected with respect to the free end of lever 85, by means of an adjustable rod 90 and a member 91. Simultaneously the quill, cop, bobbin or spool is stopped from rotation by the lifting of pulley 61 from contact with drive wheel 60, as shown at the left hand side of Figs. 7 and 8. This is accomplished by the functioning of the following parts. The free end of arm 85 is provided with a knocker finger 92, which (as connection 90 moves upwardly to stop the thread carrier) moves to the left

in Figs. 8 and 20 one end of pivotal lever 93. This lever 93 has pivoted thereto a link 94, slotted at its free end to receive the pin 95 of a detent 96 pivoted upon rod 97, which latter is carried by a pivotal arm 98. As the link 94 is moved to the left in Fig. 20, the detent 96 is moved in the path of travel of rotary kickoff 99, fixed to the shaft 20 carrying wheel 60. As the wheel 60 rotates, a tooth of said ratchet 99 kicks to the left in Fig. 20, the detent 96 and rod 97. This rod 97 also is arranged in the slotted part of a pivoted and vertical trip arm 100, best seen in Fig. 19, the working end of which is provided with a tooth 101 normally engaging a notch 102 of a member 103 carrying vertical, spring actuated rod 104. This rod is movable, when released, through a bracket 106 secured at 105 to quill holder 57, see Fig. 17, so that when the part 107 of rod 104 abuts against part 108 of bracket 106, pulley 61 is raised free of wheel 60. Taking up now the automatic swift stop to prevent breaking of thread in the event of tangling thereof, and referring to Fig. 2, (right hand side) thread 69 is guided to thread carrier box 68, through an eye 110 upon a wire 111 secured to machine frame 1. In case of tangling of thread upon swift 70 the wire 111 is pulled inwardly and moves member 112 around its pivot 113, thus drawing downward by connection 114, the lower arm 115 of a bell-crank lever, the upper arm 116 being connected as at 117 to the free end of a pivotal lever 118 carrying a socket 119 fitted to which is a wire having a bent-up end 120. With the movement of pivotal lever 118, arm 93, see Fig. 20, is caused to operate link 94 whereupon detent 96 is moved into the path of travel of rotary kick off 99 to stop the rotation of shaft 20 and thereafter a quill, or the like as is readily apparent. Thus as a swift 70 stops the above described parts coact to cause part 120 to impinge against the squared end 121 of pivotal lever 79, see Figure 2, and trip the parts shown in said figures as previously described with respect to thread carrier box stoppage, to cause the split feed nuts 89 to become disengaged from the lead screw 51. The various operated parts just described may be re-set manually by means of lever 122 which is operatively connected therewith. Upon completion of the travel of carrier 68 in a direction toward the right or, in other words, to the finishing operation of winding thread upon a quill, said carrier 68 moves to the right in Fig. 9, the upper end 123 of a trip lever which is pivoted as at 124, whereupon the lower end 125 of said trip lever to raise the free end of wire 120 previously referred to and which is seen also in Fig. 8, to cause functioning of the kick-off parts previously described with reference to Fig. 20, and repetition of which is unnecessary.

To release carrier 68 after completion of its travel lever 126, see Figs. 9, 11 and 12, which is pivoted at 126' to carrier 68, is manually operated to abut against stop 127 in which 5 position, through the instrumentality of various connecting parts braking device 127' is released from engagement with the upper of the split feed nuts 89. At such time as the feeding mechanism is disengaged with 10 respect to carrier 68 it is desirable that the carrier be prevented from working too freely. Referring now to Fig. 15, the carrier 68 is provided with an offset within which are arranged oppositely disposed, spring 15 pressed, friction plungers 84 for impinging against guide rod 84'. The frictional contact of said spring pressed plungers may be increased or diminished by adjusting screws 84². Referring again to Figs. 8, 11, 12, 13, 20 and 19 and to the operation of setting pulley 61 in operation at the same time with carrier 68, it is to be noted that when hand lever 122 is moved to raised position said lever causes arm 130 (see Fig. 8) which is 25 pivoted as at 131 to lever 122, to move upwardly and thereafter move crank 132 about its pivot point 133. This causes pin 134 upon crank 132 to move one end of previously described arm 85 upwardly around its 30 pivot point 86 whereupon braking device 84 previously referred to is disengaged from the upper of the split feed nuts 89 with the result that the carrier 68 is in proper position for functioning with respect to a quill 35 or the like. It is to be further noted that at the same time hand lever 122 has moved lever 135 (see Fig. 8) around its pivot point 136 with respect to lever 122 with the result that bell crank lever 137, the lower end of 40 which moves in the slotted part 137' of lever 135, is caused to move about its pivot point 138, so that its upper arm 138' (see Fig. 19) causes detent 102 carried by part 100 (kick-off) to engage in notched part 102 45 of member 103 whereupon pulley 61 is placed in position for functioning at the same time as carrier 68. It is to be further noted that when lever 85 is lowered to starting position, plunger 129, the face of which 50 is bevelled as at 129, (see Fig. 13) is moved inwardly to pass lever 130 which is pivoted at 131, and that when starting lever 122 is raised plunger 129 is caused to raise lever 130 around its pivot 131 to reset the horizontal, 55 spring pressed plate 78 previously described.

It will now be apparent that we have devised a novel and useful construction in an automatic winding machine, which embodies 60 the features of advantage enumerated as desirable in the statement of the invention and the above description, and while we have, in the present instance, shown and described preferred embodiments thereof which will 65 in practice give satisfactory and reliable

results, it is to be understood that the same are susceptible of modification in various particulars without departing from the spirit or scope of the invention or sacrificing any of its advantages. 70

Having thus described our invention what we claim as new and useful and desire to secure by Letters Patent, is:—

1. In a winding machine, a quill, means including a floating drive to rotate said 75 quill, a carriage, means to reciprocate the carriage, a thread carrier box for said carriage, means to effect step by step advance of said carrier box during carriage reciprocation, a vertically disposed, pivotal thread 80 carrier within said carrier box mounted to move inwardly under the influence of gravity upon thread breakage and multiple quick acting trip mechanism common to said quill operating and carrier box operating means, 85 connected with respect to said thread carrier and operative to stop said quill and carrier box.

2. In a winding machine, a quill, means including a floating drive to rotate said 90 quill, a carriage, means including a box cam to reciprocate the carriage, a thread carrier box for said carriage, means to effect step by step advance of said carrier box during carriage reciprocation, a vertically disposed, 95 pivotal thread carrier within said carrier box, mounted to move inwardly under the influence of gravity upon thread breakage and multiple quick acting trip mechanism common to said quill operating and carrier 100 box operating means, connected with respect to said thread carrier and operative to stop said quill and carrier box.

3. In a winding machine, a quill, means including a floating drive to rotate said 105 quill, a carriage, means to reciprocate the carriage, a thread carrier box for said carriage, means including step-up gear wheels for imparting different speeds and to effect step by step advance of said carrier box 110 during carriage reciprocation, a vertically disposed, pivotal thread carrier within said carrier box mounted to move inwardly under the influence of gravity upon thread breakage, and multiple quick acting trip mechanism 115 common to said quill operating and carrier box operating means, connected with respect to said thread carrier and operative to stop said quill and carrier box.

4. In a winding machine, a quill, means including a floating drive and eccentric gear wheels to rotate said quill, a carriage, means to reciprocate the carriage, a thread carrier box for said carriage, means to effect step by 120 step advance of said carrier box during carriage reciprocation, a vertically disposed, pivotal thread carrier within said carrier box mounted to move inwardly under the influence of gravity upon thread breakage, and multiple quick acting trip mechanism com- 125 130

- 6 mon to said quill operating and carrier box 10 operating means, connected with respect to said thread carrier and operative to stop said quill and carrier box.
- 5 5. In a winding machine, a quill, means including a floating drive to rotate said quill, a carriage, means to reciprocate the carriage, a thread carrier box for said carriage, means to effect step by step advance of said carrier 10 box during carriage reciprocation, a vertically disposed, pivotal thread carrier within said carrier box mounted to move inwardly under the influence of gravity upon thread breakage, and trip mechanism common to said quill operating and carrier box operating means, connected with respect to said thread carrier and operative to stop said quill and carrier 15 box, and other mechanism operative between said swift and said trip mechanism to stop said quill and carrier box in the event of thread tangling.
- 20 6. In a winding machine, a spindle, head-drive, mechanism including a main drive shaft and a stud shaft and also including a floating drive for rotating said quill, a universal coupling for said shafts, a carriage, means to reciprocate the carriage, a thread carrier box for said carriage, means to effect step by step advance of said carrier box during carriage reciprocation, a vertically disposed, pivotal thread carrier within said carrier box mounted to move inwardly under the influence of gravity upon thread breakage and trip mechanism common to said quill operating and carrier box operating means, connected with respect to thread 25 carrier and operative to stop said quill and carrier box.
- 25 7. In a winding machine, a quill, means including a floating drive to rotate said quill, an inclined fixed track paralleling the longitudinal axis of said quill, a thread carrier 30 part movable therealong to equalize tension of thread upon quill as fed thereto from a thread carrier, a carriage, means to reciprocate the carriage, a thread carrier box for said carriage, means to effect step by step 35 advance of said carrier box during carriage reciprocation, a vertically disposed, pivotal thread carrier within said carrier box mounted to move inwardly under the influence of gravity upon thread breakage, and multiple quick acting trip mechanism common to said quill operating and carrier box operating means, connected with respect to said thread carrier and operative to stop said quill and carrier box.
- 40 8. In a winding machine, a pivotal quill spindle, means including a floating pulley carried by said spindle, means including a drive wheel having a curved periphery for driving said pulley, a carriage, means to reciprocate the carriage, a thread carrier box 45 for said carriage, means to effect step by step advance of said carrier box during carriage reciprocation, a vertically disposed, pivotal thread carrier within said carrier box mounted to move inwardly under the influence of gravity upon thread breakage, and trip mechanism common to said quill operating and carrier box operating means, connected with respect to said thread carrier and operative to stop said quill and carrier box.
- 50 9. In a winding machine, a quill, means including a floating drive to rotate said quill, a carriage, means to reciprocate the carriage, a thread carrier box for said carriage, means to effect step by step advance of said carrier box during carriage reciprocation, a vertically disposed, pivotal thread carrier within said carrier box mounted to move inwardly under the influence of gravity upon thread breakage, multiple quick acting trip mechanism common to said quill operating and carrier box operating means, connected with respect to said thread carrier and operative to stop said quill and carrier box, and a manually operable lever for resetting said trip mechanism.
- 55 10. In a winding machine, a reciprocatory carriage, a lead-screw, a thread carrier movable with said carriage, a split feed nut also carried within the thread carrier box cooperating with the lead screw, a thread carrier within said box and normally maintained in vertical position by a strand of thread and adapted under the influence of gravity to move inwardly around a pivot upon breaking of said thread, a plurality of successively arranged trip-devices operatively arranged to release said nut from said lead screw, and means cooperative with said thread carrier to set in motion said trip devices when said thread carrier moves from vertical position.
- 60 11. In a winding machine, a reciprocatory carriage, a lead-screw, a thread carrier box movable with said carriage, a split feed nut carried within the thread carrier box cooperating with the lead screw, a pivotal thread carrier within said box and normally maintained in vertical position by a strand of thread and adapted under the influence of gravity to move inwardly around its pivot upon breaking of said thread, a plurality of successively arranged quick acting trip-devices operatively arranged to release said nut from said lead screw, means cooperative with said thread carrier to automatically set in motion said trip devices when said thread carrier moves from vertical position, and manually operable means for resetting said trip devices.
- 65 12. In a winding machine, a reciprocatory carriage, a lead-screw, a thread carrier box movable with said carriage, a split feed nut carried within the thread carrier box cooper-

- ating with the lead screw, a pivotal thread carrier within said box and normally maintained in vertical position by a strand of thread and adapted under the influence of gravity to move inwardly around its pivot upon breaking of said thread, a plurality of successively arranged quick acting trip-devices operatively arranged to release said nut from said lead screw, means cooperative with said thread carrier to automatically set in motion said trip devices when said thread carrier moves from vertical position, a quill holder pivotally arranged opposite said thread carrier box, a floating pulley carried thereby, a drive wheel normally engaging said pulley, means cooperative with said trip devices for disengaging said pulley from its drive wheel, and manually operable means for resetting said trip devices.
13. In a winding machine, a reciprocating carriage, a lead-screw, a thread carrier box movable with said carriage, a split feed nut carried within the thread carrier box cooperating with the lead screw, a pivotal thread carrier within said box and normally maintained in vertical position by a strand of thread and adapted under the influence of gravity to move inwardly around its pivot upon breaking of said thread, a plurality of successively arranged quick-acting trip-devices operatively arranged to release said nut from said lead screw, means cooperative with said thread carrier to automatically set in motion said trip devices when said thread carrier moves from vertical position, a quill holder pivotally arranged opposite said thread carrier box, a floating pulley carried thereby, a drive wheel normally engaging said pulley, means co-operative with
- said trip devices for disengaging said pulley from its drive wheel, an inclined track supported by said quill holder, a thread guide movable with the thread carrier box and provided with rollers for tracking upon opposite sides of said track, and manually operable means for resetting said trip devices.
14. In a winding machine a quill, a carriage operable to reciprocate before said quill, a thread carrier box including a thread carrier upon said carriage for presenting thread to said quill, a main driving shaft, means including eccentric gear wheels for rotating said shaft at variable speeds during winding of thread upon said quill, whereby said quill is rotated at slow speed during presentation of thread to the "high" portion of the quill and is rotated at fast speed during presentation of thread to the "low" portion of the quill.
15. In a winding machine a swift, a quill, a carriage operable to reciprocate before said quill, a thread carrier box including a thread carrier upon said carriage for presenting thread to said quill, a main driving shaft, means including eccentric gear wheels for rotating said shaft whereby said swift is operated at uniform speed and said quill at variable speeds during winding of thread thereupon, whereby said quill is rotated at slow speed during presentation of thread to the "high" portion of the quill and is rotated at fast speed during presentation of thread to the "low" portion of the quill.

In testimony whereof we have hereunto signed our names.

JEAN JOSEPHS.
DAVID T. BERLIZHEIMER.
